KNITTING MACHINE

William Richter, Kankakee, Ill., assignor to Paramount Textile Machinery Co., Chicago, Ill., a corporation of Illinois

Application November 14, 1938, Serial No. 240,219

7 Claims. (Cl. 66—144)

This invention relates to circular knitting machines and more particularly to a mechanism for delivering to the needles of a knitting machine, a continuous single thread formed of separate lengths of threads of different weight, kind or color or combinations thereof for the purpose of forming zones of fabric in the knitted article of differing composition or color. In particular it relates to such a mechanism comprising means to select from a plurality of yarn sources any desired yarn, and means to tie said selected yarn to any of the remaining yarns which is then being fed to the knitting station.

The principal object of the invention is to provide a mechanism that will accommodate a larger number of different kinds or colors of yarn than has heretofore been possible.

Another object is to provide a mechanism that can be adapted from those presently employed with a minimum of reconstruction.

Still a further object is to provide such a mechanism including means to prevent entanglement of the substantially larger number of threads accommodated while they are being fed to the selecting means.

Another aim is the provision of means included in such mechanism to select any one of the several yarns accommodated without danger of breakage of the parts thereof by mis-timing of the mechanism.

The device constituting the present invention is an improvement in the thread selecting device disclosed in United States Letters Patent granted to Walter Larkin No. 1,624,792 of April 12, 1927, No. 1,726,396 of August 27, 1929, No. 1,841,249 of January 12, 1932 and No. 1,949,314 of February 27, 1934. Those patents describe thread selecting and knotting devices of the general class referred to above and capable of selecting any one of four differently colored threads being fed from as many bobbins; to feed them to the knitting needles in one continuous strand by knotting each succeeding yarn to its predecessor, and without stopping the machine.

By its very nature the mechanism of the Larkin patents mentioned hereinabove is limited to the selection of no more than four yarns and, in the extreme, perhaps five. However, for certain classes of work it is desirable to select as many as eight yarns or more in which cases the construction of Larkin cannot be employed for reasons which will become apparent as the description proceeds.

In the following description I do not intend to limit myself to the selection of differently col-

ored yarns for forming horizontal stripes in stockings, but may employ threads of different weight or kind. Nor do I intend to limit myself to any particular type of knitting machine, as for example the ribber of Larkin for forming stringwork, but may adapt my invention to other types of machines, as for example, those for forming plain knit fabric in stringwork, for forming complete stockings having a heel and toe pockets and combining both plain and rib knitting, or to flat machines. Nor do I intend to confine myself to the combination of my invention with the particular knotting mechanism disclosed here or in Larkin since it will appear that my selecting means is capable of being associated with other types of knotting or thread joining instrumentalities.

In the drawings:

Figure 1 is a side elevation of a knitting machine including the present improvement; 20

Figure 2 is a rear elevation of the machine;

Figure 3 is a detail on somewhat enlarged scale showing the yarn gathering arm operating mechanism;

Figure 4 is a detail in side elevation of the 25 yarn guiding fingers and some associated parts;

Figure 5 is a partial plan view of the yarn selecting fingers and mechanism associated therewith, and

Figure 6 is a detail in plan view of the auxiliary yarn guiding mechanism. 30

In these drawings I have, for clarity, omitted or broken away inconsequential portions.

Now referring to Figure 1, numeral 10 indicates generally the knitting head of the machine comprising the needles, either cylinder or cylinder and dial, the cylinder or cylinder and dial therefore, the cam box as well as other mechanism conventionally employed in knitting a stocking or part thereof. Attached by an arm 11 to the bed-plate 12 of the machine is the thread selecting and knotting mechanism generally referred to as 13, to which detailed reference will now be made.

Mounted in the bracket 11 is a post 14 on 45 which is attached a box-like frame 15. Passing through the frame 15 is the spindle 16 on which is journaled the bell-crank lever 17, its downwardly depending arm 18 being connected at 19 by a pivot to the link 22. The opposite end of 50 link 22 is pivotally connected at 23 to the free end of a rocker arm 24 journaled at 25 on the frame of the machine. Arm 24 has projecting therefrom an arm 26 carrying a follower roller 27 normally bearing on an endless link chain 28 55

carried on a sprocket 28. Sprocket 28 is stepped along intermittently to move the chain 28 past the roller 27 by a ratchet and pawl, not shown, but standard on substantially every machine to which this invention may be adapted. The movement of the chain in relation to the follower 27 governs the pattern to be knit, e. g. the width and colors of stripes in the stocking or the areas to be knit of the different selected 10 yarns.

Carried on chain 28 are lugs 32a to 32h inclusive of different heights relative to the center of sprocket 28 so that as each lug passes under the roller 27 the arm 24 is rocked over various 15 angles depending upon the height of the then functioning lug.

It will be understood that these lugs need not necessarily be spaced as shown but may be arranged differing distances apart or in any particular order of sequence, the sequence determining the stage in the knitting of the article at which a particular one of the yarns is to be introduced, and the height of the lug the particular yarn to be then selected. Lugs 32a, etc. 20 are removable from the chain and may be assembled in any desired sequence or spacing on the chain.

The other arm 33 of lever 17 is connected at 34 to a rod 35 whose downwardly bent extremity 36 enters with a sliding fit a hole 38 in cylinder 37, whereby upon rocking of lever 17 the member 36 and cylinder 37 act together as a dashpot to absorb shock and overtravel to facilitate 30 rapid and frequent positioning of lever 17. Cylinder 37 is pivoted at 39 to allow for the various angular positions taken by rod 35. A spring 42 between arm 33 and the frame of the machine urges lever 17 in a clockwise direction and its associated rocker 24 counter-clockwise to maintain roller 27 in contact with chain 28 and lugs 32a, etc.

Affixed to the lower end of arm 18 is an arcuate segmental selector cam 43 (Figures 1 and 5) wider at its base at point of attachment and 45 narrowing to its extremity as shown. In engagement with said cam is the follower 44 mounted in a rod 45 (Figure 5) guided by and slidable laterally in the sides of the frame 15. Fixed to the rod 45 by a screw clamp joint 46 and serving to maintain the same from rotating about its axis, is the arm 47, the other U-shaped end of which substantially embraces an annular recess 48 of a hub 49 forming part of a yarn guide finger selecting cam 52. Spring 53 attached to the 50 frame and to rod 45 constantly urges follower 44 into contact with its cam 43.

Arranged side by side on a shaft 62 fixed in the sides of the frame 15 and adapted to rock thereon is a plurality of yarn guide fingers 63a, 63b, etc., each comprised of a support 64 on which is carried the extended portion 65 curved upwardly as shown to receive the yarn passing through an eyelet 66 in the end thereof. Springs 67, one individual to each finger 63a, etc.; normally urge said fingers in a clockwise direction against a stop rod 68. Cam 52 is of a width sufficient to engage only one at a time of said fingers 63a, etc.

Rotatable on spindle 16 is a bevel gear 72 (Figure 3) to which is connected the link 73 by means of a pivot 74. At its lower extremity the link 73 is pivoted at 75 to rocker 76 adapted to reciprocate about spindle 39. A pawl 77 pivoted at 76 on rocker 76 is urged against surface 82 by a spring 83. Surface 82 is part of a controller

cam 84 affixed to lever 85 journalled on spindle 39. Lever 85 is pivotally connected at 86 to link 87 extending from arm 33 of bell crank lever 17. Mounted on constantly rotating shaft 92 is an eccentric 93 whose yoke 94 is fastened to connecting rod 95. Said rod 95 at its other end is pivoted on rocker 96 rotatable on spindle 39. At its lower end rocker 96 is provided with a lug 97 and at its upper end with a portion 98 adapted to bear against an adjustable stop screw 102 10 carried in an arm 103 of rocker 76.

Affixed in bevel gear 72 is a lateral rod 112 passing through a hole 113 in cam 52 and having a sliding fit therewith so that while cam 52 is free to be positioned at any point longitudinally 15 of rod 112, it can still be rotated on its shaft 16 simultaneously with rotation of gear 72.

A spindle 122 is affixed at 123 to the frame 15 and rotatably carries a bushing 124 to the inner end of which is attached the bevel pinion 125 20 in mesh with gear 72. Rotatably mounted on bushing 124 is another bushing 126 carrying at its outer end a yarn gathering member 127. A screw 128 taking into spindle 122 maintains the several parts in operative relation axially while 25 permitting them to rotate freely. Inserted in bushing 124 is a stud 132 and in bushing 126 a stud 133 between which studs extends a coil spring 134 constantly urging stud 133 and hence bushing 126 with its member 127 against a stop 30 129 forming part of the frame. Normally, i. e. when bevel gear 72 is at rest, stud 132 is against edge 135 of a rectangular slot 136 in the inner edge of bushing 126. Stud 132 is substantially 35 smaller in diameter than the circumferential width of slot 136 for a purpose to be presently described.

Yarn gathering member 127 cooperates with a knotting mechanism indicated generally by 142, which, although part of the present invention, is not claimed per se and will be described by reference to the aforementioned Larkin patents which disclose details thereof and the relationship with those portions of the machine forming the principal subject matter of the present invention. 45

Mounted on a convenient support 152 held by the frame of the knitting machine are the yarn bobbins 115a to 115h inclusive, from each of which are fed the yarns a, b, c, etc. Said yarns pass upwardly through eyelets 154 in a support 155 and thence to an auxiliary guiding and aligning means now to be described.

Carried in the frame of the machine is a support 156 (Figure 6) of substantially bifurcated shape, each arm of which carries a plurality of eyelets 157 and 158. Forming part of the support 156 and on the side nearest the yarn sources is an aligning member 162 comprised of alternating substantially semicircular channels 163 as clearly shown in Figure 2, one for each yarn. Disposed between the arms of member 156 is a rod 164 bearing a plurality of pairs of friction discs 165 of a common type, one pair for each 50 yarn, and spaced freely from each other on the rod 164 by springs 166. Springs 167 and 168 restrained by fixed collar 172 and adjustable collar 173 maintain discs 165 in lateral position in alignment with eyelets 157 and 158. 55

Yarns a, b, c, etc., after leaving the bobbins are guided and aligned by channels 163 into eyelets 157, between discs 165, through eyelets 158 to pass through eyelets 66 from whence all but one are gathered in a group and jointly held in clamping means forming part of knotting mech- 75

anism 142. It will be noted that the one excepted yarn, as for example, *c*, is at a given moment being fed to the needles of the machine.

Operation of the apparatus as detailed will now be described. It will be assumed that a yarn *c* is being fed to the needles of the machine and that it is desired to introduce to the knitting station one of the other yarns to be selected from *a*, *b*, *d*, *e*, *f*, *g* and *h*. For convenience let *f* be the one to be introduced.

At the time such new selection is to be made the lug 32*f* on chain 28 is brought beneath the follower 26 by rotation of sprocket 29 whereupon lever 24 is rocked clockwise and through link 22 rocks crank 17 counter-clockwise. Accordingly cam 43 permits its follower 44 through spring 53, rod 45 and yoke 47, to slide selector cam 52 laterally.

It will be remembered that lugs 32*a*, etc., are of different heights so that the motion transmitted to move cam 43 will rotate the same to a position whereat cam 52 is positioned directly over the yarn finger 63*f*, carrying yarn *f*.

Simultaneously with the positioning of cam 52, crank 17 actuates link 87 and thereby its associated controller cam 84 to permit the pawl 77, then idling on surface 82, to drop into position to be actuated by lug 97. At this time the link 95 is moving to the right, as seen in Figure 1 by means of eccentric 93 and thereupon upon movement to the left the lug 97 engages pawl 77 to thereby operate rocker 76 clockwise and its link 73 upward.

Upon such upward movement of link 73 bevel gear 72 is, through the pivot 74, rotated clockwise to rock the rod 112 and its associated cam 52 in the same direction. Cam 52 then operates the finger 63*f* downward to bring yarn *f* into the path of yarn gathering member 127 (Figure 1).

Simultaneously with rotation of gear 72 pinion 125 and its associated bushing 124 also rotate in a counter-clockwise direction as viewed in Figure 2. Accordingly pin 132 also rotates until it engages the upper edge of slot 136 whereupon further rotation of said pin carries with it sleeve 126 and yarn gathering member 127 in the same direction of rotation. Consequently when member 127 approaches yarn *f* it is carried into the knotter mechanism 142, tied to the then feeding yarn *c* and thence to the knitting station, all as explained in the aforementioned Larkin patents.

In prior mechanisms the member 127 was made integral with pinion 125 so that immediately upon rotation of gear 72, cam 52 and pinion 125, the member 127 likewise began to rotate. Accordingly, there was little, if any, time delay between actuation of a finger 63*a*, etc.; and its associated yarn into the path of member 127 and the movement of said member to gather said yarn. As a result, the number of yarn fingers 63*a*, etc.; and hence selectable yarns was limited to four or five; otherwise the member 127 reached yarn gathering position at almost the same time as the yarn was brought into position to be gathered. In such cases malfunctioning by failure of the member 127 to pick up the yarn intended to be selected, or entanglement from improper pickup of the yarn occurred. For proper operation the yarn should be located in the path of member 127 well before the latter reaches gathering position.

This desired relationship or timing is obtained by the improvement of this invention. By the cooperation of the pin 132 and slot 136 the pin 132 is permitted to move the difference between

the width of the slot and the diameter of the pin before member 127 is actuated and it is this time delay that permits the selected finger 63*a*, etc. to bring its yarn properly into the path of member 127 before the latter picks up the yarn.

By the introduction of such time delay it is possible to use six or more fingers 63*a*, etc. depending upon the requirements of the machine. It will be understood that the time delay may be adjusted by changing the width of the slot 136 or the diameter of the pin 132 or both.

Although I have illustrated the invention as applied to a machine wherein yarn selection is primarily controlled through a pattern chain it will be appreciated that such selection may be attained by a pattern drum having cam surfaces of certain contour or any equivalent selecting means.

The yarn guiding means shown particularly in Figure 6 acts to segregate each yarn from its neighbor by the channels 163, which function as partitions between the yarns to prevent entanglement prior to their reaching the position guiding eyelets 157. It will be appreciated that in practice bobbins 115*a*, etc., are disposed at random on the support 152 so that the yarns feeding therefrom may cross each other in their transit to eyelets 157. Depending upon the relationship of the yarn bobbins with respect to eyelets 157, the grooves 163 may be arranged fan-wise, i. e. divergent at the ends at which the yarns enter and converging towards the eyelets 157, so as to subject the several yarns to a natural guiding movement as they run from a number of widely spaced bobbins into the relatively narrow grouping of eyelets 157.

I claim:

1. In a knitting machine, a series of knitting instrumentalities, a group of yarn sources, pattern controlling mechanism, means controlled by said mechanism to select one of said yarns; means to join one of said yarns in transit to the knitting position to another yarn selected from the group including means to sever said fed yarn after joining; a gathering member to carry said newly selected yarn into joining position and timing means associated with said gathering member to delay the action thereof beyond the actuation of the yarn selecting means.

2. The structure of claim 1 in which said timing means comprises a member operated simultaneously with said yarn selecting means and having a projection adapted to engage a slot in said gathering member, said projection being smaller than said slot.

3. The structure of claim 1 in which said timing means comprises a member operated simultaneously with said yarn selecting means and having a projection adapted to engage a slot in said gathering member, said projection being smaller than said slot and tension means to urge said gathering member to a normally inactive position.

4. The structure of claim 1 in which said timing means comprises a member operating simultaneously with said yarn selecting means and having an element adapted to engage a co-acting element in said gathering member, the member first mentioned and the gathering member adapted to rotate with respect to each other on a common axis, and the said elements being separated a predetermined angular distance with respect to said axis.

5. The structure of claim 1 in which said timing means comprises a member operating simul-

- aneously with said yarn selecting means and having an element adapted to engage a co-acting element in said gathering member after a predetermined time interval.
5. 6. In a knitting machine, knitting instrumentality, a group of yarn sources, means to select at least one of said yarns for introduction into knitting position, means to join said yarn or yarns to the yarn or yarns then in transit to knitting position, a gathering member to carry said newly selected yarn or yarns into joining position and timing means to delay the action of the gathering member beyond the actuation of the yarn selecting means.
7. In a knitting machine, knitting instrumentality, a group of yarn sources, means to select any of said yarns for presentation to knitting position, mechanism to join said selected yarn to a yarn then in transit to knitting position, means for directing said selected yarn to said joining mechanism, said first and second means being actuated from a common source, and timing mechanism between said first and second mentioned means to delay the action of said directing means beyond the actuation of said selecting means.

WILLIAM RICHTER.
